UNITED STATES PATENT OFFICE.

CARL F. NAYER, OF CHICAGO, ILLINOIS, ASSIGNOR TO WILLIAM E. KIER, OF CHICAGO, ILLINOIS.

TYPE-FEEDING DEVICE.

1,414,148.

Specification of Letters Patent. Patented Apr. 25, 1922.

Application filed November 1, 1920. Serial No. 420,866.

To all whom it may concern:

Be it known that I, CARL F. NAYER, a citizen of the United States, residing in the city of Chicago, county of Cook, and State of Illinois, have invented a new and useful Improvement in a Type-Feeding Device; and I do hereby declare that the following is a full, clear, and exact description of the same, reference being had to the accompanying drawing, and the numerals of reference marked thereon, which form a part of this specification.

My invention relates more particularly to an attachment adapted to be applied to a printing press for printing names and addresses on letters, or envelopes. In the past it has been customary to print form letters for advertising or other purposes by leaving a blank space for the name and address for the person to whom it was to be sent; the name and address being later filled in by a typewriter or other means, and as it has been impossible to secure correspondence between the printed form and the address by such a method, the character of the letter would at once be apparent to the receiver.

My invention is designed to overcome this objection by applying an attachment or mechanism to the press that prints form letters, which mechanism is designed to supply linotype having the names and address or individual matter thereon in proximity to the type or bed plate, so that the address or individual matter is printed in proper place by type similar to that used for the body of the letter and at the same time that the body of the letter is printed.

It is therefore an object of this invention to provide a printing press with mechanism for supplying linotype in proximity to the type bed plate.

It is a further object of this invention to couple the mechanism with the driving means of the press for automatic operation therewith.

It is broadly an object of this invention to provide a printing press with means for printing individual matter on letters or circulars, etc., whenever the same is required.

It is also an object of this invention to provide means for disposing of the used linotype.

It is likewise an object of this invention to provide a novel form and arrangement of mechanism that is compact, efficient and simple in operation possessing numerous advantages which will become more apparent from the following description and disclosures in the drawings.

Other and further important objects of this invention will be apparent from the disclosures in the drawings and specification.

The invention (in a preferred form) is illustrated in the drawings and hereinafter more fully described.

In the drawings:

Figure 1 shows an elevational side view of a printing press for printing form letters embodying my invention.

Figure 2 is a top plan view of Figure 1 showing my invention upon an enlarged scale, and omitting parts of the printing press.

Figure 3 is a section through a part of the mechanism involving my invention showing the operation of certain features, on an enlarged scale.

Figure 4 is an enlarged section through the linotype feeding mechanism showing the relation of certain features.

Figure 5 is a fragmentary view showing the top plan view of the ramming mechanism and the linotype holders in section.

Figure 6 is a section on the line 6—6 of Figure 5.

Figure 7 is a section on the line 7—7 of Figure 5.

Figure 8 is a section on the line 8—8 of Figure 2.

Figure 9 is a perspective view of the linotype holders showing supporting frame members in section.

Figure 10 is a horizontal section through the ram used in my invention, but showing the same in split views, one half representing the ram in one position and the other half representing the ram in another position.

Figure 11 is a section on the line 11—11 of Figure 3 showing an adjustment for the ram.

Figure 12 is a detail view showing the linotype holders and operating mechanism for the linotype in one position.

Figure 13 is a view similar to Figure 12 but showing the linotype operating mechanism in a different position.

Figure 14 is a perspective view of the front part of the linotype holders.

Figure 15 is a section on the line 15—15 of Figure 4.

Figure 16 is a section on the line 16—16 of Figure 6 showing the linotype holding latches.

Figure 17 is a perspective view of a type bed plate with my linotype projected into position.

Figure 18 is a block of linotype in the form in which it is contemplated projecting the same.

Figure 19 is a section on the line 19—19 of Figure 10.

Figure 20 is a sectional detail on the line 20—20 of Figure 2.

Figure 21 is a perspective view of the linotype holders.

As shown in the drawings:

Referring now more specifically to the drawings in which similar reference numerals refer to similar features in the different views, the numeral 1, in Figure 1 represents a printing or embossing press, of usual construction having a type plate 2 and platen 3 which is connected to a gear 4 by means of a link 5. The plate 2 is designed to receive the form type and have an inking ribbon drawn thereover, and the form letters are pressed between the ribboned plate and the platen 3 when the latter is oscillated into contact therewith as is well known in the art. While embossing presses are adapted and used to print form letters by using a ribbon, they change their function when so used, so the press used with my invention will herein be termed a printing press or device. My invention comprises mechanisms driven by gear 4 and so timed that a block of linotype consisting of several lines 45 is projected adjacent the type plate 2 as shown in Figure 17 during every oscillation of the platen 3, whereby a name and address or some individual or special matter may be printed simultaneously with the printing of the body of the letter.

While this mechanism may assume different modifications, I have illustrated in the present embodiment of my invention a ram or reciprocating element 6 operated by a cam 7, secured on a shaft 8 supported by a bracket 9 secured to the press 1. Said cam being so constructed that said ram will stop at intervals, or dwells at predetermined points. A gear 4^a is secured on shaft 8 and meshes with gear 4 for rotating the shaft and said cam 7. The ram 6 is slidingly supported upon a base or runway 11, leading to the type plate 2 (see Figures 3 and 8) secured to the press in suitable manner, the base 11 having guideways 12 formed by pro-

jecting flanges 62, in which the ram operates, and guide plates 13 overlapping the outer portions of the ram 6. The rear part of the ram is preferably provided with a cam contacting roller 14 mounted in a bifurcated 70 and adjustable attaching member 15 (see Figure 11); an adjustable wedge 16 operated by a screw 17 is located between the bifurcated member 15 and the end of the ram 6 which has an inclined portion 18 against 75 which the inclined part of the wedge 16 is located. By properly adjusting the wedge 16, the ram will be adjusted to operate the linotype the proper distance on account of the slotted bolt holes.

The ram is operated in the forward direction by the cam 7, and the return movement is effected through the instrumentality of a weight 19, which always keeps the roller 14 in contact with cam 7 and which is supported by a chain 20 trained over a pulley 21 and connected to the ram 6 by means of a stud 22; the pulley being rotatably mounted upon the printing press in any approved manner. The forward end of the ram 6 is 90 designed to contact with the linotype in the act of projecting the same in line with the type plate 2, and to securely hold the linotype, a latch member 23 is provided on each side of the forward part of the ram. These 95 latch members 23 are preferably set in recessed portions in the sides of the ram and they are provided with right angled claws or projections 24 adapted to enter cut out portions or depressions 25 in the ends of the 100 linotype. The opposite or rear ends of the latch members 23 are provided with abutments 26 which are designed to contact with compression springs 27 mounted in grooves 28 in the ram 6 and abutting against 105 end flanges 29 at the corners of the ram as shown in Figure 10 which shows the ram divided into two parts for the purpose of illustrating the relation of the latch members and the linotype at both the forward 110 and initial points of travel. In the forward position as exemplified in the upper half of Figure 10, the springs 27 have a tendency to hold the linotype tightly against the front end of the ram 6; while in the initial position the springs 27 are compressed 115 to allow the claws 24 to move forwardly so that a block of linotype can readily fall into position. The compression of the springs is effected through a pair of pins 30 secured 120 in the base 11 and extending through the slots 28 in position to engage the latch abutments 26 as the same are moving rearwardly as shown in the lower half of Figure 10. The forward end of the ram 6 is further 125 provided with a pair of slots 31 for a purpose to be later described.

Co-operating with the ram above described, I have illustrated a plurality of linotype holders as comprising a further 130

part of my mechanism. These holders are preferably located and suitably supported adjacent the rear part of the bed plate and comprise a pair of end plates 32 secured adjacent the opposite inner walls 33 of a U-shaped base 34. These end members have spaced flanges 35, 36 and 37 projecting inwardly thereof to provide a pair of linotype holders, the rear one being for new linotype, 5 called the feeding holder, and the forward one for used type and called the storage holder. The aforescribed base member 11 extends forwardly in a peculiar curved formation to conform to parts of the press and 10 at the forward end the same is provided with a grooved horizontal portion 38 having a pair of slots 38^a; the groove being designed to receive the ram 6 underneath the linotype holders as shown in Figure 6. The 15 end plates 32 have their lower ends provided with grooves 39 opening inwardly to receive the ends of the ram 6. The U-shaped base 34 has oppositely directed side flanges 40 which are supported on the base portion 20 38 and each flange is provided with a plurality of grooves in the lower face thereof to receive spring pressed detents 41 and 42, (see Figures 6 and 16). The 25 detents 42 represent the ones used in the rear or new linotype holder A, while the detents 41 represent the ones in the forward or used linotype holder B. As shown, the detent 41 slides on the base 38 and enters an aperture in the end plate 32 of the 30 holder and projects a short distance therein; the end thereof being bevelled upwardly so that when a used linotype is projected upwardly in said holder, the detent can be cammed back against the spring 43 to admit 35 the used linotype in the holder after which it may snap back to hold the linotype in place. The spring 43 may be held in place by a screw 44 or any other appropriate means. The detent 42 likewise slides on the 40 base 38 and is designed to enter an aperture in the adjacent end plate 32 when in released position. But detent 42 is normally held in retracted position by means of a pin 45 having one end screwed into 45 the detent and the other fitting in a countersunk hole in the base portion 38. A compression spring 46 presses against the outer end of the said detent 42, and being held in position by a screw 47 screwed in 50 a flange 40. The function of this detent 42 is to keep the linotype in the holder when the latter is filled by the operator. The holder is usually swung rearwardly on its pivot when being refilled as shown in Figure 1, thus raising pin 45 so that spring 46 can slide the detent 42 inwardly to obstruct the new linotype as they are dropped into the holder. For this purpose, the linotype holder is pivotally mounted upon its rear 55 side, by means of hinge lugs 48 on the flanges 40 of base member 34 in any appropriate manner, and to secure the holder in position so that it may be released and swung rearwardly, the same is provided with a pair of rods 49 pivoted to trunnions 50 intermediate the upper and lower ends of said holder. These rods extend rearwardly where they are adjustably secured in a clamping mechanism 50^a mounted upon the journal bearings of shaft 8 (see Figure 2). In Figure 20, I have illustrated one form of clamping mechanism which may be used, the same comprising a sleeve 51 having a shouldered head 52 and a threaded end 53, supported upon spaced brackets 54, one adjacent the head 52 and the other adjacent the screw threaded end 53; and a sleeve member 55 surrounding the sleeve 51 between the said supports 54. Holes are bored diametrically through these sleeves 55 to slidingly admit the rods 49. And relative longitudinal movement of these sleeves will firmly clamp the rods in said holes. Relative sliding movement of the sleeves is effected through the instrumentality of a hand operated knob 56 threaded upon the end of sleeve 51 with its inner end abutting one of the brackets 54; an operating handle 57 inserted in a hole in the knob 56 may be used in turning the knob. 60 The used linotypes are adapted to be forced upwardly into the holder B by a plurality of timed devices which comprise a further part of my mechanism; and while these devices may be widely varied, I have illustrated in the present embodiment of my invention a pair of spaced levers 58 fulcrumed by means of a bearing 59 rotatably supported upon the base 11 in a bearing 11^a as shown in Figures 3 and 8. The bearing 59 has an arcuate flange 60 on each side, to which the levers are secured, and these flanges have at their outer ends, horizontally extending arcuate beads or ridges to fit in arcuate grooves 61 in a side of the levers 58. The levers 58 and bearing 59 have a working fit between the flanges 62 formed on the base 11 and extending inwardly thereof. By this arrangement, the levers are constrained to operate as a unit. These levers are provided at their rear ends with rollers 63 mounted upon pintles 64 (see Figure 15) secured in bifurcations formed by the ends of the levers and blocks 65 bolted to the levers. Cams 66 are mounted on the shaft 8 and are adapted to strike the rollers 63 to operate the levers 58 at the proper time to raise the forward ends thereof. The base support near the rear end of each lever 60 is provided with a yieldingly supported plunger 67 mounted in a suitable bore, having a spring 68 at the bottom thereof to constantly force the plunger upwardly. The upper end of each plunger is designed 65 70 75 80 85 90 95 100 105 110 115 120 125 130

to press against a lever 58 tending to force the forward end down after the same has been elevated by the cam 66. The levers have their upper surfaces receding on a bevel from the center line in order to meet the requirements of the structure in producing a compact arrangement, and the ram 6 is provided with grooves in its under surface which terminate in the aforementioned slots 31 to receive said levers 58 during portions of their operative strokes. The forward ends of the levers are provided with raised contact portions 69 and 70, the portion 69 being higher than the portion 70.

15 In connection with the aforescribed mechanism, I have provided means whereby the operating mechanism of the press may be stopped when the unused linotype holder A is depleted of linotype. For this purpose (see Figure 5) the ram 6 is provided with a bar 71 having a narrow forward end 72 designed to enter an aperture 73 leading into the holder A, and a contact arm 74 secured at right angles thereto at the rear end. This bar 71 is held in position on the ram 6 by means of a plate 75 secured to the ram 6, and a yielding operative connection is provided between the bar 71 and plate 75 by means of a spring 30 76 secured by a pivot to the plate 75 at one end thereof and abutting a shoulder in a slot in the bar 71 as shown in Figure 5. The arm 74 is adapted to contact at certain times with an insulated contact piece 77 secured to a guide plate 13 by bolts 78 which are insulated. The insulation of the piece 77 and bolts 78 is such that no electric current can pass through the plate 13 as shown in Figure 7. A wire 40 79 is shown connected to the piece 77, and this wire may be part of a signal or bell circuit or a solenoid switch circuit for throwing the operating motor of the press out of action, and the contact arm 74 may be grounded. I have not illustrated the signal or bell nor the switch mechanism nor the motor since the same are well known in the arts. Accordingly, as long as any linotype remains in the holder A, the end 72 50 of the arm 71 will abut thereagainst and prevent contact of the arm 74 and piece 77; but as soon as the holder A is depleted, the end 72 will enter the aperture 73 far enough to bring the pieces 74 and 77 into contact 55 and close the switch circuit to ring the signal or bell or stop the motor; the spring 76 providing a yielding connection whereby the operation of the ram is not stopped by the contact or the obstruction of bar 71.

60 Operation: Assuming that the rear compartment or holder A has been filled with linotype, and the printing press is in operation, the gear 4 will drive shaft 8 through gear 4^a and if ram 6 is in the position illustrated in the lower half of Figure 10, a

block of linotype, having an address thereon as shown in Figure 18, will be dropped in place by the levers 58 between the claws 24 and the end of the ram, the ram 6 having a dwell at this point whereby it remains stationary for a short interval, since it will be in contact with a concentric portion 80 of cam 7. Further rotation of cam 7 will advance the linotype to the position shown in the upper half of Figure 10 where the same will have been projected in line with the type in plate 2 as shown in Figure 17 and upon a platform 81 forming a part of the runway 11 and extending through a slot in the wall of the printing press, and the cam 7 will have rotated to bring the portion 82 thereof into contact with the ram roller 14, and the platen 3 of the printing press will be at this time in position to press a form letter paper against the inking ribbon type plate 2. After the letter has been printed, the platen 3 will recede from the type plate 2 and the weight 19 will withdraw the ram according to the contour of cam against which the roller 14 is held by the said weight, and when the ram has been withdrawn until the block or plurality of linotypes is directly under the forward or used linotype holder B, the roller 14 will be contacting with the concentric portion 83 of cam 7, whereby the ram will have another swell and remain stationary for a short interval to allow the levers 58 which will be now operated by the cams 66 to ascend through the slots 38^a and 31 and lift the linotype past the yielding detents 41 and into the holder B, holding the same for a short interval with portion 70 holding the linotype in holder A as shown in Figure 4; the detents snapping immediately back in position to securely hold the used linotype in said holder. During this operation of the levers 58, the ram 6 will be withdrawn as shown in Figures 10 and 4 and after the cam 66 has passed out of contact with the rollers 63 on the rear end of the levers 58, the yieldable plungers 67 will force the forward end of the levers 58 downwardly with a fresh block of linotype resting on the portions 70 and which block of linotype will be gently deposited in position in front of the ram 6 as shown in the lower half of Figure 10 while the levers pass on through the slots 31 and 38^a to the position shown in Figure 12, and the mechanism will begin another cycle of operations. The ram 6 advances a block of linotype during every oscillation of the platen 3, caused by a complete rotation of gear 4. When the last block of linotype in the holder A has been used and the operator has not noticed it and stopped the press, a signal will be given or the press will be automatically stopped by the aforescribed means since the end of the bar 71 will not be obstructed now by

the linotype after it has passed through the aperture 73 and the switch circuit will be closed by the contact of arm 74 and block 77 which can now be brought together. If 5 it is now desirable to remove the used linotype from the holder B and insert new linotype in the holder A, the head 56 of the clamp mechanism 50^a may be rotated to release the rods 49 whereby the same may 10 slide further through the clamping mechanism to allow the holders to pivot rearwardly as shown in Figure 1 in dotted lines. After the holder B has been emptied and the other refilled, the holders may be swung 15 back and clamped in position by the head 56 as is now obvious; after the letters are written the used linotype may be used to print addresses on the envelopes.

It will accordingly be observed that I have 20 devised novel mechanism whereby a form letter may have an address printed thereon simultaneously with the printing of the body of the letter, or whereby, an address may be printed on an envelope which is also automatic in its action, and easily adapted for application to existing printing or embossing presses or incorporated in new machines.

I am aware that numerous details of construction may be varied through a wide 30 range without departing from the principles of this invention and I therefore do not purpose limiting the patent granted otherwise than necessitated by the prior art.

I claim as my invention:

35 1. In a printing device having a type plate, the combination with the driving mechanism thereof, of means connected therewith for projecting type in the plane of said plate and comprising an adjustable reciprocating element and means for supplying type to said element.

40 2. In a printing device having mechanism for printing form letters, the combination with the driving mechanism thereof, of a driving device connected thereto, an element periodically operated by said device for advancing type in operative relation with said first mentioned mechanism and removing the same therefrom and means for 45 supplying type to said element.

50 3. In a printing device having mechanism for printing form letters, the combination with the driving means thereof, of a device driven thereby, an element operatively controlled by said device and having dwells at predetermined points in its operative course for receiving and discharging type.

55 4. In a printing device having mechanism for printing form letters, the combination with the driving mechanism thereof, of linotype storage devices and means operatively associated with said driving mechanism for receiving blocks of linotype from one of said storage devices and projecting the same

in operative relation with said first named 65 mechanism, and means for discharging the same into the other storage device.

5. In a printing device, the combination with the driving mechanism thereof, of type feeding mechanism operatively connected thereto and comprising a reciprocating element having dwells for receiving and discharging type, and a timed and pivoted device adapted for discharging the type from 70 said reciprocating element. 75

6. In a printing device having mechanism for printing form letters, a driving mechanism, linotype feeding mechanism driven thereby and comprising a reciprocating element having a dwell for receiving linotype 80 and projecting the same in operative relation with said first mentioned mechanism.

7. In a printing device having a type plate and platen, driving mechanism for said platen, linotype feeding mechanism driven 85 by said driving mechanism and comprising a ram having means for engaging linotype and projecting the same in line with said type plate in timed relation with the operation of said platen. 90

8. In a printing device for printing form letters, the combination with the driving mechanism thereof, of linotype feeding and discharging mechanism driven thereby and comprising a feeding element having a discharging dwell, and a discharging element operating in timed relation with said dwell for ejecting type from said feeding element. 95

9. In a printing device for printing form letters, the combination with the driven 100 mechanism thereof, of linotype feeding and discharging mechanism operatively associated therewith, and comprising a reciprocating ram for feeding linotype and a pivoted lever member operating in timed relation therewith for discharging linotype from 105 said ram.

10. In a printing device having a type plate and oscillatable platen co-operating therewith to print form letters, a pair of 110 type holders, linotype in one of said holders, a ram for projecting said linotype in line with said type plate during the oscillation of said platen, and withdrawing the same under the other holder, and a timed lever member for projecting said linotype in said 115 other holder.

11. In a printing device for printing form letters, the combination with the type plate thereof, of a pair of linotype holders, linotype in one of said holders, means for conveying said linotype adjacent said type plate and returning the same under the other holder and means for projecting the same into said other holder. 120 125

12. In a printing device having a type plate, a pair of linotype holders, a cam operated and adjustable ram having a dwell

under one of said holders for receiving a linotype and projecting the same adjacent 5 said type plate, and returning the same under the other holder, and a cam operated lever device for projecting said linotype into the other holder.

13. In a printing device, a pair of linotype holders, a feeding ram having a plurality of slots, a cam for operating said ram 10 in one direction, a weight for operating said ram in the other direction, said cam being so constructed that said ram will have a dwell under each holder, and pivoted levers and means for operating the same in timed relation with said ram and operating through 15 said slots for discharging linotype into one of said holders.

14. In a printing device having a wall, with a type plate secured to said wall and a 20 slot above said type plate, a platform extending through said slot, a pair of linotype holders supported above said platforms, linotype in one of said holders, and mechanism for feeding said linotype through said 25 slot and discharging it thereafter into the other holder.

15. In a printing device, a feeding linotype holder, a storage linotype holder having yielding detents for holding linotype 30 therein, a feeding device for receiving linotype from said feeding holder, and mechanism for discharging the same into said receiving holder past said yielding detents.

16. In a printing device having a type 35 plate, a runway leading to said type plate, a ram on said runway, means for periodically operating said ram with dwells at predetermined points and means for supplying linotype at one of said points, and discharging the same at the other point.

17. In a printing device having a type plate, a runway leading to said type plate, a linotype feeding holder on said runway, a linotype storage holder on said runway, a 45 linotype conveying ram on said runway for feeding linotype to said type plate, mechanism for operating said ram with dwells under each holder for receiving linotype from the feeding holder, and allowing the 50 same to be discharged into the storage holder.

18. In a printing device, a feeding linotype holder, a storage linotype holder having yielding detents, means for receiving linotype from the feeding holder for projecting the same to the printing device and thereafter returning the same under the feeding holder, and means for elevating the linotype into the storage holder past said 60 yielding detents.

19. In a printing device, a type holder, means for pivoting the same upon said device and clamping and adjustable mecha-

nism for said holder whereby the same may be swung on its pivot.

20. In a printing device, a feeding linotype holder, a reciprocating ram having means for entering said holder when the same is empty and a device co-operating with said means when the same has entered 65 said holder for making an electrical contact.

21. In a printing device, a feeding linotype holder, a reciprocating ram, having a yieldable device for entering said holder, when the same is empty, a support, means on 70 said support and ram designed to be brought into contact when said device has entered said holder for indirectly causing said ram to stop.

22. In a printing device, a pair of linotype holders, linotype in one of said holders, means for projecting said linotype from one of said holders and withdrawing the same to the other holder and means for ejecting the linotype into said other holder and carrying 75 linotype from the first mentioned holder in position before the said means.

23. In a printing device, a feeding linotype holder, a storage linotype holder, a runway for supporting the same, a reciprocating element mounted on said runway for advancing linotype on the feeding runway and a pivoted device for projecting linotype into said storage holder and conveying linotype from the feeding holder to said runway.

24. In a printing device, a type plate, a runway leading thereto, a storage linotype holder mounted on the runway, a feeding linotype holder mounted on the runway, reciprocating means for advancing linotype from the feeding holder to said type plate and withdrawing the same to the storage holder, a pivoted lever having a plurality of raised portions for ejecting linotype into the 90 storage holder and conveying linotype from the feeding holder to said runway.

25. In a printing press, a reciprocating type carrying member having yieldable type retaining means for forming a type holding 100 recess, and a stop coating with said means for expanding said type holding recess.

26. In a printing press, a feeding type holder, a storage type holder, a type carrier, a lever mechanism operating in timed relation with said carrier for feeding type to said carrier and discharging the same therefrom.

In testimony whereof I have hereunto subscribed my name in the presence of two 120 subscribing witnesses.

CARL F. NAYER.
